UNITED STATES PATENT OFFICE.

JAMES T. CLARK, OF DETROIT, MICHIGAN, ASSIGNOR OF ONE-HALF TO GEORGE S. GRITMAN, OF DETROIT, MICHIGAN.

GARMENT-DISPLAY FIXTURE.

1,255,584.

Specification of Letters Patent.

Patented Feb. 5, 1918.

Application filed January 7, 1915. Serial No. 923.

To all whom it may concern:

Be it known that I, JAMES T. CLARK, a citizen of the United States, residing at Detroit, county of Wayne, State of Michigan, have invented a certain new and useful Improvement in Garment-Display Fixtures, and declare the following to be a full, clear, and exact description of the same, such as will enable others skilled in the art to which it pertains to make and use the same, reference being had to the accompanying drawings, which form a part of this specification.

This invention relates to display fixtures for wearing apparel and its object is a device for holding a quantity of coats or other garments that is comparatively inexpensive and of simple construction and which occupies but little space in comparison to the number of garments stored thereon.

In many devices now in use for a similar purpose, the clothes are supported by hangers on racks which are pulled out into the aisle-way to display the goods and that may be again returned to the original position to maintain the aisle-way free from obstruction. With applicant's device the clothes hangers are mounted on revoluble supports of such form that clothing suspended therefrom by means of such hangers extends a greater radial distance upon one side than upon the other whereby in revolving the support the side of longer radius is brought to display position extending into the aisle-way, or, if the stand be placed in a cabinet, extending outside of the said cabinet where they may be readily examined and, then, by simply turning the support on its axis, the clothing is removed from the aisle-way or returned within the cabinet as the case may be.

A further object of the invention is a form of support by means of which a greater number of garments may be carried than is possible with forms now generally in use. Another object of the invention is a display stand having two independent supports one directly over the other and both of the peculiar form above mentioned, whereby clothing on either the upper or lower support may be independently brought into view without disturbing the other support or garments thereon. These objects and the various novel features of construction by means of which they may be attained are hereinafter more fully described

and claimed and shown in the accompanying drawings in which—

Figure 1 is a front elevation of my improved display fixture positioned within a cabinet.

Fig. 2 is a side view of the fixture showing the cabinet in cross-section and illustrating how either support may be turned and the suspended garments brought into view.

Fig. 3 is a section taken on line $x-x$ of Fig. 1, showing my improved form of support by means of which a large number of garments may be carried and also showing clearly how rotation of the support may bring the garments out into an aisle-way or to such position that they extend out from the garments on similar racks on either side.

Fig. 4 is a vertical section of the display fixture.

Fig. 5 is a plan view of the fixture showing the upper and lower garment supports.

Fig. 6 is a detail showing the method of removably fastening the lower support to the stand.

Similar characters refer to similar parts throughout the drawings and specification.

The device is shown in detail in Fig. 4, and consists of a comparatively heavy iron base 1, preferably secured in any approved manner to a wooden base member 2 of proper size to insure stability of the fixture. Secured centrally in the base member 1 is a vertical rod 3 held from turning in the base by means of a set-screw 4. In the upper end of the base member 1 is formed a ball-race 5 and a similar ball-race 6 is secured to a tube 7 encircling the rod 3 and carrying at the upper end the garment supporting member 8. The weight of the member 8 and garments thereon are thus carried by the ball-bearings on the base and the support is thus readily rotatable relative to the rod. Secured to the rod 3 above the support 8 is another ball-race 9 held in position by a set-screw 10 and a ball-race 11 is provided attached to the tube 12 carrying the garment support 13 at the upper end thereof, and the garments on this support and the weight of the parts is all carried by the ball-bearings between the raceways 9 and 11. By this arrangement the two garment supports are revoluble independently one of the other.

In some it is desired to hang long gar-

ments, such as an overcoat, from the upper support. In such instances it is necessary to remove the lower supporting member 8 and for this reason the supporting member 8 may be made removable from the stand as hereinafter shown. The supporting members 8 and 13 are tubular in cross-section and of U shape or horse-shoe form as shown in Figs. 3 and 5, and the radius of 10 the circular part of the support is greater than the distance of the ends of the arms from the center of revolution allowing a considerable number of garments to be placed on the two ends of the support 15 greater in number than the quantity possible of being supported on the circular part thereof, the garments lying parallel and close together as shown in Fig. 3 near the ends of the support while a less 20 number only may be carried in radial position on the circular part of the support. The form of the support therefore enables a greater number of garments to be carried than if the support were in the form of a 25 circle. Also by reason of the two ends or arms of the support being less in length than the radius of the circular part, and also by reason of the garments extending outward from said circular part in radial 30 manner, simply rotating the support on its axis will bring the garments out into an aisle-way or from within the cabinet, as the case may be, to display position. By arranging the fixture with upper and lower 35 supports, the lower support may be rotated to bring the garments thereon out from in under the garments on the upper support, thus making them accessible without having to reach under the upper garments. 40 All of the garments are preferably suspended on the supports by hangers now commonly in use.

The supports are carried by arms 14, 14 etc., from a central hub 15 secured to the 45 tubes 7 or 12 in either instance. If it be desired to make the lower support removable, as before stated, the hub may be made in the form shown in Fig. 6, in which the arms 14 are each secured to one-half of the split hub 50 member 16, the opposite half 16^a being bolted to the part 16 and a set-screw provided by means of which the hub is secured to the tube. By removing the part 16^a the entire support may be removed from the stand.

55 In Fig. 5 is shown a plan view of the two supports, one of which has the semi-circular part turned outwardly, the other of which is turned in the reverse position.

Having thus briefly described my invention, what I claim is—

60 1. A garment display device comprising

a casing open in front, a vertically positioned standard therein, and a U shaped garment support rotatably mounted thereon, the standard being positioned forward of 65 the vertical center line of the case whereby, upon revolution of the support, the garments upon the circular side thereof are brought outwardly from the case to view, and upon turning the open side of the support toward 70 the front of the case the garments are positioned entirely therewithin.

2. A display fixture for wearing apparel and the like comprising a base member, a vertically positioned standard in fixed relation therewith, and a pair of vertically spaced, independently revoluble garment supports mounted thereon, said supports being U shaped in form substantially as and 75 for the purpose described.

3. A garment fixture comprising a casing having a display side, a garment supporting member revolvably mounted therein, the garment support being adapted to hold the garments on the forward part thereof parallel 85 with the display side to present the fronts of the garments to view and the remaining part of the garment support being adapted to hold the garments in radial position about the center of revolution, the center of revolution of the support being forward of the 90 center line of the casing whereby, upon turning the same, the radially positioned garments are brought outward through the display side of the case.

4. In a display fixture for wearing apparel and the like, a substantially U shaped supporting member revolvable in a horizontal plane, said U shaped member enabling the garments to be carried in parallel relation at 100 the ends thereof and in radial relation on the curved portion.

5. In a display fixture for wearing apparel and the like, a garment supporting member substantially U shaped in form revolvable in 105 a horizontal plane, the center of the curved portion practically coinciding with the center of revolution, and the two ends of the support extending substantially parallel from the point of union with the curved portion 110 allowing the garments supported therefrom to lie substantially parallel from the said center to the ends of the arms and to occupy a radial position about the circular portion of the support substantially shown 115 and described.

In testimony whereof, I sign this specification in the presence of two witnesses.

JAMES T. CLARK.
